UNITED STATES PATENT OFFICE.

HERBERT N. KILBY, OF CLEVELAND, OHIO.

CARBONATING APPARATUS.

Application filed June 11, 1923. Serial No. 644,615.

The present invention is directed to improvements in carbonating apparatus, and particularly to one designed for the continuous carbonation of alkaline sugar juice.

5 The primary object of the invention is to provide an apparatus of this character which is composed of a few parts so arranged that the carbonation of the sugar juice will be effectively and rapidly performed.

10 A further object of the invention is to provide an apparatus of this character constructed in such manner that the carbonic acid gas will flow constantly during the carbonation of the juice and will be intimately commingled with the juice during the carbonation process.

15 As is well known in the carbonation of sugar juice the juice is thoroughly mixed with lime and afterwards subjected to the action of carbonic acid gas which causes the impurities held in solution in the juice to settle in the apparatus, thereby producing a juice which is clear.

20 25 With these and other objects in view, as will appear as the description proceeds, the invention consists in the novel features of construction, combinations of elements and arrangements of parts, and hereinafter to be 30 fully described and pointed out in the appended claim.

In the accompanying drawing:

Figure 1 is a vertical sectional view through the apparatus, and

35 Figure 2 is a detail vertical sectional view through the head controlling device.

Referring to the drawing 1 designates the carbonating vessel, the lower end of which is tapered as at 2 and has associated therewith a valved outlet 3 through which deposits of heavy material may be drawn off. Fixed in the vessel above the lower end thereof is a screen 4 which serves to check the upward flow of the sugar juice and carbonic acid gas and further causes the same to intimately mix.

The top 5 of the vessel is equipped with a pipe 6 through which excess gases can pass from the vessel to atmosphere.

40 45 50 A casing 7 is fixed to one side of the vessel 1 and communicates with the interior thereof through the opening 8, said casing having a hinged lid 9 to permit access to be had to said casing for sampling the sugar juice

when desired. Associated with the casing 7 is a pipe 10 through which the carbonated sugar juice is drawn.

Disposed adjacent the vessel 1 is a tank 11, the lower end of which is provided with a valved outlet 12 to permit heavy matters to be withdrawn therefrom, there being a screen 13 fixed in said tank to check the upward flow of liquid and at the same time mix the gas with the juice.

55 60 65 Mounted upon the upper end of the tank 11 is a plate 14 which has an annular wall 15 to produce a passage 16 and disposed concentrically with the wall 15 is a cylinder 17 which rests upon said plate. Confined between the wall 15 and cylinder 17 is a 70 quantity of mercury 18 which provides a liquid seal for the dome 19, said dome being formed from aluminum and envelops the wall 15 for slidably receiving the same. A cover plate 20 closes the upper end of the 75 cylinder 17 and is provided centrally with a stuffing box 21.

70 75 80 Arranged upon the cover plate 20 is a casing 22, said casing having located therein a tapered nozzle 23, the purpose of which will appear later.

85 90 Mounted upon the upper end of the casing 22 is a cylinder 24, the top of which has mounted therein for threaded adjustment a sleeve 25, there being a stuffing box 26 carried by the top of the casing 22 and disposed in alignment with said sleeve.

95 100 A stem 27 is provided and has its lower end fixed to the dome 19, said stem being slidable in the stuffing boxes 21 and 26 and in the sleeve 25. This stem has adjustable thereon a disk 28 upon which the lower end of the coil spring 29 rests, the upper end of said spring bearing against the disks 30 which slidably engages said stem and is engaged by the lower end of the sleeve 25, whereby when said sleeve is adjusted movement is imparted to the disks 30 so that the tension of the spring 29 can be varied.

105 The stem 27 is further provided with a flow regulating disk 31 which cooperates with the nozzle 23 to regulate the flow of carbonic acid gas therethrough, this gas being conducted to the casing 22 from the supply pipe structure 32. This pipe structure is provided with valves 33 and 34, and when both valves are open there will be a constant flow of gas through the nozzle 23 owing to

the fact that the diameter of the controlling disks 31 is less than the smallest diameter of the nozzle 23. Thus it will be observed that when the disk is in its lowered position 5 as shown in Figure 1, the periphery thereof is annularly spaced from the wall of the nozzle 23, and consequently there will be a constant flow of gas from the casing 22 through the gas outlet pipe 35 which extends 10 downwardly into the vessel 1 so that its lower end will extend through the screen 4, and lies in a plane with the lower end of the sugar juice conducting pipe 36. The pipe 36 leads from the tank 11 into which the 15 limed sugar juice is initially received. Communicating with the lower end of the tank 11 is a T connection 37 and connected thereto is the lower end of the sugar juice supply pipe 38 which leads from a suitable supply 20 tank containing a sufficient head of juice to assure uniform velocity, and a carbonic acid gas pipe 39 connected to a constant source of supply to assure a uniform velocity.

Connecting the T connection 37 and pipe 25 structure 32 is a carbonic acid gas conducting pipe 39, said pipe having a valve 40 associated therewith, a similar valve 41 being associated with the pipe 38, whereby the flow of fluid through the respective pipes can be 30 controlled and regulated. It will thus be seen that the gas and juice will commingle in the T connection 37 and then pass into the tank 11.

The tank 11 is provided with a sight gauge 35 42 so that the liquid level within the vessel 1 and tank 11 may be observed and maintained at the level of the line A, there also being a faucet 33 carried by the tank 11 to permit a sample of the juice to be drawn 40 during the carbonating process.

The apparatus is designed more particularly for carbonating beet sugar juice, but is not necessarily limited to such use since the same can be effectively used for carbonating other fluids by using a kiln gas which varies in the per cent of carbonic acid 45 gas in the gas.

The operation of the apparatus is as follows:

50 The limed sugar juice flows from the pipe 38 into the T connection 37 and mixes with the carbonic acid gas flowing into said connection from the pipe 39. This mixture flows upwardly into the tank 11 until the 55 juice maintains a level at A. This juice flows downwardly through the pipe 36, and simultaneously therewith a quantity of carbonic acid gas flows from the casing 22 through the pipe 35 and meets the mixture 60 flowing from the pipe 36. The lower ends of the pipes 35 and 36 are engaged in the inverted pan 44 which has its flange 45 formed with serrations 46, which serve to break up gas from the pipe 35 into bubbles 65 so as to mix gas into juice coming from the

tank 11. It will be observed that since the pipe 36 is sealed to the level A with juice that the gas not absorbed by the juice in the tank 11 will rise through the passage 16 and act upon the dome 19 which will cause the 70 controlling disk 31 to rise as the pressure increases thereby increasing the opening in the nozzle 23 to permit a larger flow of gas therethrough. The gas used is from a lime kiln and contains a percentage of unabsorptive 75 gas which is not affected by the lime oxide which is mixed with the juice entering the pipe 38, and it is this gas that operates the dome 19 to control the position of the disk 31 with respect to the nozzle 23. The 80 gas not absorbed in the vessel 1 will pass out through the pipe 6. As the dome rises the spring 29 offers resistance thereto according to the percentage of carbonic acid in the gas. This pressure is always greater 85 the lower the percentage of carbonic acid in the gas. The valve 40 is so regulated that the juice entering the tank 11 will absorb all of the carbonic acid gas from the pipe 39. If a kiln gas of 20% carbonic acid and 80% 90 unabsorptive gas is used the valves 40 and 41 are so regulated that all of the carbonic acid in the gas is absorbed and the lime oxide in the juice in the tank 11 is reduced 95 20%. It will be assumed that this takes 100 cubic feet of 20% carbonic acid gas and since all of the carbonic acid gas is absorbed there will remain 80% of the gas mixed with the juice in the tank 11. Now if the 100 cubic feet entering the tank 11 is under pressure 100 of 5 lbs. per square inch the pressure of the unabsorbed gas in said tank will be 4 lbs. per square inch.

The lime oxide in the juice will be reduced 105 20% and that remaining in the juice will be taken from the vessel 1 by the pipe 35. Assuming that the valves 40 and 41 are open to the same extent and the carbonic acid gas increases to 40% and 60% unabsorptive gas so that 100 cubic feet contains twice as much 110 carbonic acid gas. This will leave about 60% lime oxide in the juice entering the vessel 1, the remaining lime oxide in the juice being taken out through the pipe 35. All 115 of the carbonic acid gas in the 40% gas that enters the vessel 1 is absorbed and leaves 60% unabsorbed gas. If the 40% gas is under the same pressure as before 5 lbs. to the square inch, the unabsorbed gases mixed in the tank 11 will have a pressure of 3 lbs. 120

From this it will be observed that the higher the gas is in carbonic acid the lower the pressure will be of unabsorbed gases. When the pressure of the spring 29 is such 125 that the disk 31 is permitted to rise to a position in a plane with the upper surface of the nozzle 23, which is the right area for 20% gas, and the pressure decreases as with 40% gas the disk will move downwardly in the nozzle thereby decreasing the volume of 130

gas flowing through the nozzle into the pipe 35 and thence into the vessel 1.

The valve 40 is never closed when the apparatus is in operation so that a quantity of 5 carbonic acid gas flows continuously into the tank 11 and meets the sugar juice in the T connection 37, which mixture flows into the carbonating vessel 1, and the alkalinity of the juice is determined by any suitable 10 device. The flow of juice can be regulated by the valve 41 and if the alkalinity is found to be less than required more juice can be used until the required alkalinity is obtained.

The upper part of the tank 11, above the 15 liquid level A, may be provided with a valve 47 which, in the operation of the apparatus, may be left partly open so as to restrict the outflow of the unabsorbed gases from the tank 11. This provides a controlled outlet 20 for the unabsorbed gases which does not interfere with the operation of the diaphragm 19 nor the building up of sufficient pressures

within the upper part of the tank 11 to operate the diaphragm or dome 19.

What is claimed is:

In apparatus of the class described, a carbonating vessel, an alkaline sugar juice receiving tank in communication with the vessel, a pipe for conducting said juice from the tank to the vessel, a casing carried by the 25 tank, a pipe structure for conducting a partially absorptive carbonic acid containing gas to the casing, a pipe for conducting gas from the casing to the vessel, means for simultaneously conducting sugar juice and a 30 partially absorptive gas of substantially equivalent pressures to the tank, and means operable by the unabsorbed gases released from the sugar juice in the tank for varying the flow of gas from the casing into the 35 40 gas conducting pipe leading to the vessel.

In testimony whereof I affix my signature.

HERBERT N. KILBY.
